ATTORNEY

UNITED STATES PATENT OFFICE

152,873

DESIGN FOR A CONCRETE MIXING MACHINE OR THE LIKE

George A. Fleischmann, Milwaukee, Wis., assignor
to Chain Belt Company, Milwaukee, Wis., a
corporation of Wisconsin

Application June 17, 1947, Serial No. 139,765

Term of patent 14 years

(Cl. D14—3)

To all whom it may concern:

Be it known that I, George A. Fleischmann, a citizen of the United States of America, residing at Milwaukee, county of Milwaukee, State of Wisconsin, have invented a new, original, and ornamental Design for a Concrete Mixing Machine or the like, of which the following is a specification, reference being had to the accompanying drawings, forming part thereof. In the said drawings:

Fig. 1 is a perspective view looking toward the loading end of the concrete mixing machine of my new design; the skip shown in dotted lines being in a lowered position; and

Fig. 2 is a perspective view looking toward the

discharge end of the concrete mixing machine. The dominant features of my design are shown in full lines.

I claim:

The ornamental design for a concrete mixing machine or the like, substantially as shown and described.

GEORGE A. FLEISCHMANN.
